UNITED STATES PATENT OFFICE.

DAVID BIRCHENOUGH, OF PATERSON, NEW JERSEY, ASSIGNOR OF ONE-FOURTH TO ALBERT RICHARD SMITH, OF SAME PLACE.

AUTOMATIC VENT AND COMBINED TAP.

SPECIFICATION forming part of Letters Patent No. 655,953, dated August 14, 1900.

Application filed March 23, 1900. Serial No. 9,850. (No model.)

To all whom it may concern:

Be it known that I, DAVID BIRCHENOUGH, a citizen of the United States, residing in Paterson, in the county of Passaic and State of New Jersey, have invented certain new and useful Improvements in Automatic Vents and Combined Taps; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to cocks or faucets, and it has reference particularly to cocks or faucets employed for drawing liquids from kegs, barrels, and other similar closed containers.

20 The invention consists in the improved faucet and in the combination and arrangement of its various parts, substantially as will be hereinafter described and finally embodied in the clauses of the claim.

25 Referring to the accompanying drawings, in which corresponding characters of reference indicate like parts, Figure 1 is a view of a portion of a barrel, showing my improved faucet and air supplying or venting means applied thereto. Fig. 2 is a longitudinal sec-

30 tional view of said faucet. Fig. 3 is a vertical sectional view of said faucet, taken transversely through that portion thereof which contains the plug or spigot. Fig. 4 is a hori-

35 zontal sectional view through the key-receiving portion of the faucet, the key and certain stops therefor being shown. Fig. 5 is an enlarged view of a portion of the inner end of the faucet, the same being partly shown in section; and Fig. 6 is a view of a certain tap or plug that is driven into the barrel and constitutes a portion of the air-supplying means.

40 The cock or faucet is designated in the accompanying drawings by the reference character *a*. It has the usual tapering enlargement *b*, which when the faucet is driven into the bung-hole *c* of the head *d* of a barrel *e* snugly fits the same. Near its inner end the 45 plug or faucet is provided with a series of annularly-disposed perforations *f*, and in the

inner end of the duct or bore *g* of said faucet is a plug *h*, of somewhat less diameter than that of the bore or duct and having a threaded head *i*, which being screwed into the bore 55 or duct of the faucet may be so adjusted as to bring the plug opposite some or all of the perforations, so as to more or less restrict the flow of the liquid. The plug is provided with a transverse slot or recess *j*, adapted to receive a certain key, hereinafter described. It should be remarked that the plug is normally set slightly back of the end of the bore or duct, so as to be safe against being unintentionally disturbed. 60

65 *k* designates the controlling plug or spigot of the faucet. This plug is of tapering form and is disposed vertically in the faucet, with its reduced end uppermost, being secured in place by a keeper *l*, which is screwed into the bottom of the faucet and between which and the end of said plug or spigot is disposed a packing *m*. Said spigot or plug is penetrated by a transverse port or orifice *n*. By simply turning the plug a quarter of a revolution the 70 passage through the faucet is either opened or closed.

75 *o* denotes a key for operating the spigot or plug. The free end of this key is provided with a reduced projection *p*, adapted to seat 80 in a slot or groove *q*, formed transversely in the upper end of the plug or spigot. In order to limit the movement of the key in turning the plug, said key is provided with a laterally-projecting lug *r*, which is adapted to 85 engage stops *s*, formed in an integral key-socket *t*, that projects upwardly from the faucet. As the upper end of this socket *t* is provided with an inwardly-projecting flange *u*, which closely fits about the spindle of the 90 key and which has but a single recess *v* for admitting the lug *r*, the key after once being inserted in the key-socket and operated to turn the plug or spigot and permit the flow of the liquid from the container cannot be 95 removed until the plug has been turned back again to shut off the flow.

100 A cylindrical neck *w*, disposed between the key-socket and the body of the faucet and receiving the upper end of the spigot, is provided with two oppositely-disposed orifices *x*. In the plane of these orifices the spigot is

provided with a transversely-extending bore *y*, which when the spigot is turned registers with said orifices. In one of these orifices is screwed a nipple *z*, and in this nipple is 5 screwed another removable nipple 1.

2, Fig. 6, is a tapering tap or plug which is adapted to be driven into the upper portion of the barrel and which carries nipples 3 4, corresponding to the nipples *z* 1, the latter 10 being removably screwed into the former.

5 designates a flexible tube or pipe which connects either the nipples 1 and 4 or the nipples *z* and 3, (according to the amount of air-flow which is necessary,) the nipples in the 15 latter case being of course removed.

When the liquid is to be withdrawn from the barrel or other container, the key having been inserted into the key-socket, as above described, and applied to the plug, when the 20 key is turned the plug or spigot will be likewise turned to permit the flow of the liquid from the container. At the same time, the port *y* and the orifices *x* being made to register with each other, air will be permitted to 25 flow through the same from the atmosphere and through the tube and the tap 2 into the barrel. Air is thus admitted to the barrel as fast as the liquid is withdrawn, and the pressure inside and outside of the barrel being 30 thus maintained equal the flow of the liquid will be unimpeded.

As has been hereinbefore stated, the plug *h* can be operated so as to restrict the flow through the faucet, if necessary, and this 35 may be done by using the key *o*, whose projection *q* is adapted to fit the slot in said plug.

Having thus fully described my invention, what I claim as new, and desire to secure by Letters Patent, is—

40 1. The combination of a faucet having a spigot or plug, and also having perforations communicating with its bore, an adjustable

plug of less diameter than the bore, arranged in the same, and adapted to control the communication through said perforations, said 45 spigot and the body portion of the faucet having openings adapted to register when the spigot is operated, air-conducting means communicating with one of the openings in the body portion of said faucet at one of its 50 ends and adapted to be connected at the other of its ends to the container to which said faucet is applied, a removable operating-key for said spigot, said key having a reduced projection at one end and also having a laterally-extending lug, and the spigot having 55 a groove in one of its ends adapted to receive the projection of the key, and a key-socket on said faucet, said key-socket having an internal recessed flange adapted to engage said 60 lug, substantially as described.

2. The combination of a faucet having a controlling spigot or plug, air-conducting means controlled by said spigot or plug and adapted to be connected with the container 65 to which said faucet is applied, said faucet having perforations communicating with its bore, and an adjustable plug of less diameter than the bore, arranged in the same, and adapted to control the communication through said 70 perforations, substantially as described.

3. The combination of a faucet having perforations communicating with its bore, of an adjustable plug of less diameter than the bore, arranged in the same and adapted to 75 control the communication through said perforations, substantially as described.

In testimony that I claim the foregoing I have hereunto set my hand this 17th day of March, 1900.

DAVID BIRCHENOUGH.
